UNITED STATES PATENT OFFICE.

ADOLF BARGEBOER, OF ROTTERDAM, NETHERLANDS.

FEEDING DEVICE.

Application filed September 23, 1924. Serial No. 739,435, and in the Netherlands October 23, 1923.

My present invention relates to automatic feeding devices for cut tobacco and other material of a similar character and has for its object a simple and reliable device adapted to feed the material uniformly without consuming much energy.

In order that my invention may be clearly understood I shall proceed to describe the same in connection with a known cigarillos machine, but I wish to emphasize that the same can be applied to other types of machines as well.

On the annexed drawing, Fig. 1 is a side elevational view of a cigarillos machine of the type disclosed in my prior specification of Patent No. 1,480,490. Fig. 2 is a longitudinal sectional view of my novel feeding device, Fig. 3 a top view, partly a horizontal section of an impeller used for actuating and in this sense forming part of the feeding device, Fig. 4 a cross sectional view along the line IV—IV in Fig. 2, and Fig. 5 a horizontal section of a modified impeller.

In Fig. 1, the frame of the cigarillos machine is designated by 1. Supported in this frame is a short belt conveyor 2, and a pressure roller 3 coacting therewith for feeding tobacco into the path of a reciprocating knife 4, the cut tobacco being received by a hopper 5 whence it falls into a space 6. An impeller (7, 13) serves to push the tobacco from the space 6 to the right into a space 8, where it is engaged by a conveyor to be described in further detail hereinafter. Said conveyor moves the tobacco into a chamber 9 located in alignment therewith, a parting knife 10 being provided for separating the tobacco in chamber 9 from the body portion. The chamber 9 is hinged to the frame 1 and provided with a hinged bottom, so that, when it has swung downward through 90°, the tobacco therein may be pushed by a stamper 11 directly into the usual groove 12 of the rolling table.

The impeller (Figs. 2 and 3) is composed of a plurality of pusher bars 7 arranged side by side in a box 13 and loaded by springs 14, which tend to push them to the right. The box 13 is provided with two lugs 15 engaging a rod 16, which passes through an elongated slot of a lever 17 (Fig. 1). This lever is swung alternately to the left and to the right by a cam 19 coacting with an antifriction roller 18 on the lever 17, and by a coiled retraction spring 20, respectively. The left hand end of the impeller stroke is obviously determined by the maximum diameter of the

cam 19, its length of stroke depending upon the quantity of tobacco in the space 6 and upon the tension of spring 20.

Fig. 5 illustrates a modified construction of the impeller. The pusher bars here are designated by 21 and are pivotally coupled in pairs through triangular hinge plate 22, which in turn are pivotally coupled in pairs through larger hinge plates 23, the latter being hinged together through a large hinge plate 24. The plate 24 is pivoted to a support 25 in the box 13, which has a screw-threaded portion 26 through which it may be connected to a suitable driving member for imparting reciprocatory motion thereto.

The spring loaded pusher bars 7 or the pivotally interconnected pusher bars 21 can be adjusted to exert the same pressure on the tobacco so that the latter is uniformly fed to the conveyor. The uniformity in the feed can still be increased by allowing the impeller after each stroke, or after a predetermined number of strokes to move laterally alternately in the one and in the other direction through a distance equal to one half of the width of one pusher bar, when the end bars on both sides should have a width equal to one half of that of the others and the total width of the space, through which the tobacco is pushed to the right by the impeller, should be smaller by the same amount than the total width of the pusher bars. It will be understood that with this construction the center of each bar 7 or 21 will, after each lateral motion, engage the tobacco where this was just opposite the joint between two bars at the previous stroke.

The conveyor, which receives the tobacco from the impeller, is composed of an upper series of alternating bars 27 and 31, and a lower series of alternating bars 28 and 32. The bars 27 and 28 are provided on their working faces with forwardly inclined teeth 29 and 30, respectively, but the bars 31 and 32 have smooth working faces.

The bars of the group 31, 32 are alternately moved vertically towards and away from each other, whereas the bars of group 27, 28 are reciprocated horizontally in addition to being moved vertically towards and away from one another, it being understood that when the bars 27, 28 are moved inwards, the bars 31, 32 move outwards and vice versa. Consequently, when the toothed bars 27, 28 grip the tobacco between them, the latter is released by the bars 31, 32. Immediately

thereafter the bars 27, 28 move to the right, taking the tobacco with them. At the end of this stroke they release the tobacco, which is then immediately gripped by the group 5 of bars 31, 32, whereupon the bars 27, 28 are retracted (to the left) to again grip the tobacco, which is thereby intermittently fed on to the right and eventually pushed into the chamber 9. In practice it has been found 10 that with this feeding device the weight of the tobacco severed by each stroke of the knife 10 is approximately constant.

The mechanism for imparting the required 15 motions to the conveyor bars and to the knives has not been illustrated as this is of ordinary construction and does not form part of the invention.

If desired, the bars 31, 32 could also be provided with teeth and be moved lengthwise 20 alternately with the bars 27, 28, but in this case the tobacco would be liable to be damaged by the teeth of the one group of bars when conveyed by the bars of the other group.

It should be noted, that in the embodiment 25 shown a bar of the group 27, 28 is placed vertically opposite a bar of the group 31, 32 so as to prevent the tobacco from expanding too much when the bars of one group move away from each other.

30 What I claim is:—

1. In a device for feeding tobacco and similar material to a machine for working on the

material, an upper series of parallel conveyor bars, a lower series of conveyor bars, said 35 lower series of bars being parallel to each other and to said upper series, a plurality of gripper bars associated with each of said series and an impeller for feeding material between said series of bars, said conveyor bars being adapted to move toward each other 40 to grip the material and move it longitudinally.

2. In a device for feeding tobacco and similar material to a machine for working on the material, an upper series of parallel conveyor bars, a lower series of conveyor bars, said 45 lower series of bars being parallel to each other and to said upper series, a plurality of gripper bars associated with each of said series and an impeller for feeding material 50 between said series of bars, said conveyor bars being adapted to move toward each other to grip the material and move it longitudinally, the said gripper bars being adapted to be moved from each other to release said material, while the material is being moved longitudinally.

3. A device as claimed in claim 1 in which 55 said conveyor bars are provided with teeth, the other bars of each series having smooth working faces.

In testimony whereof I affix my signature.

ADOLF BARGEBOER.
